FUEL-FEEDING SYSTEM FOR INTERNAL-COMBUSTION ENGINES.

Application filed December 11, 1923. Serial No. 678,903.

This invention relates to improvements in fuel feeding systems for internal combustion engines, and is especially applicable to engines of this class which operate on the high compression principle, and in which heavy oil fuel is used which is injected into the combustion space at timed intervals under considerable pressure and at high velocity.

The invention aims especially to provide novel means whereby the pressure of the fluid which is supplied to the engine for combustion may be applied to secure the quick closing of the fuel valve, thus avoiding the use of a heavy spring for this purpose.

In the drawings—

Figure 1 illustrates diagrammatically one practical embodiment of the invention as applied to an engine in which fuel is injected by compressed air, and

Figure 2 is a broken sectional view of a modified fuel valve construction for solid injection.

The fuel valve construction of Fig. 1, which is the form preferably used where the fuel is to be injected by compressed air, consists of a flat-faced valve body 1 on the end of a stem 2, such stem being provided with a piston 3 on its opposite end, such piston working in a chamber 4 formed in the valve casing. The piston 3 is provided with a reduced portion 5 for seating a compression spring 6 located in the chamber 4 and bearing against the top thereof so as to exert seating pressure on valve 1. Passage 7 leading from chamber 4 is controlled by a loaded valve 8, a pipe 9 being tapped into the valve casing above valve 8 for returning to the fuel tank 12 fluid passing through the port of the valve 8. While other types of valves may be substituted for the valve 8, preferably such valve will be of a well known safety valve type, in which the velocity of the fluid passing therethrough will tend to keep the valve open until the pressure has decreased to a point considerably lower than the pressure required to open such valve.

While means other than that shown may be used for imparting pressure to the fluid supplied to the engine for combustion pur-

poses and for also controlling the opening and closing of the fuel valve above described, a fuel pump of any well-known type having a valve for by-passing to the source of supply fluid pumped during the latter part of the pressure stroke of the pump plunger, may be most advantageously used. A pump having these characteristics is shown in Fig. 1, and comprises a plunger block 10 having a discharge chamber 11 formed therein, to which fluid is admitted from tank 12 by passage 13 controlled by suction valve 14. Displacement plunger 15, operating in bore 16, and suitably packed, as usual, is reciprocated in synchronism with the engine by connections hereafter described. Pump discharge valve 17 is preferably and as shown spring loaded, as is also by-pass valve 18 and suction valve 14. Valves 17 and 18, according to the present arrangement, control the passage of fluid from chamber 11 to pipes 19 and 20, respectively, for controlling the opening and closing of the fuel valve 1. Plunger 15 is provided with a coupling nut 22 which engages with an enlargement 23 on the end of the plunger 15 and also screws onto the threaded end 24 of a crosshead 25 guided in a bushing 26 on member 27. The lower end of the crosshead is connected by pin 28 with an eccentric strap 29 on an eccentric 30 carried by shaft 31, although it will be understood that a cam drive may be used if desired. Crosshead 25 carries a pin 32 working in a slot 33 on one end of lever 34 which is mounted at its other end to turn on shaft 35, such shaft being eccentrically mounted as shown, and carrying a lever 36 connected with a centrifugal governor diagrammatically shown at 37. Push rod 38, connected by link 39 and pins 40 to lever 34 intermediate pin 32 and shaft 35, controls the by-pass valve 18.

When a pump of the kind described above is used, its capacity should be such that each outward stroke of the plunger 15 will draw into the discharge chamber 11 an amount of fluid in excess of the maximum combustion requirements of the engine, so as to thus provide a surplus of such fluid for utilization as the pressure medium to secure the

closure of the fuel valve. As the load on the engine varies, also, it is desirable that the quantity of fuel actually delivered to the combustion space should be accurately controlled in accordance with the engine load. To this end, therefore, governor mechanism of well-known type, indicated diagrammatically at 37, may be advantageously associated with the pump mechanism above described by connections consisting of lever 36, eccentrically mounted shaft 35, lever 34 and push rod 38, so as to vary the time of opening the by-pass valve 18 and thus close the fuel valve 1 by fluid pressure transmitted by pipe 20, as hereafter explained.

The operation of the apparatus as thus far described is as follows: On the outward stroke of pump plunger 15, fluid is drawn past suction valve 14 into chamber 11. Inward movement of plunger 15 will open discharge valve 17, and force additional fluid through pipe 19 against the flat face of fuel valve 1, thereby raising such valve against the pressure of spring 6. Blast air entering by pipe A will at this time, as usual, blow the fuel through the spray nozzle orifices B into cylinder C, where combustion takes place in the usual way. As pump plunger 15 continues its inward movement, push rod 38, moving in the same direction through the connections above described, will unseat by-pass valve 18. As this occurs, the pressure in pipe 20 and chamber 4 will be equalized with the pressure in pipe 19, whereby the pressure on the lower face of the fuel valve may be balanced and spring 3 be of such strength as to then force the valve 1 onto its seat, or an excess effective pressure tending to close the valve may be secured to aid the spring, as may be desired, as it is preferable that the valve be closed quickly. Further inward movement of plunger 15 will increase the pressure in chamber 4 until safety valve 8 opens, and surplus pressure fluid pumped will be returned by pipe 9 to fuel tank 12, the spring on the safety valve 8 being of such strength as to open only on such increase of pressure after the valve 1 closes. The same cycle of operations is repeated on following suction and discharge strokes of the pump.

Regulation of the amount of fuel supplied for combustion in accordance with the engine load, is automatically controlled by well known centrifugal governor mechanism above referred to and diagrammatically shown at 37, which is driven in synchronism with a moving part of the engine to which the pump supplies fuel. Thus, as the speed of the engine varies, lever 17 will move, rotating the eccentrically mounted shaft 35 so as to shift the fulcrum of lever 34 and vary the point in the stroke

of the pump plunger at which push rod 38 will unseat by-pass valve 18 to terminate injection.

The same control may be applied to engines in which the oil is injected in a solid stream without the use of compressed air. A modified form of fuel valve is shown in Fig. 2 which is efficient for such use, and which is controlled by fluid pressure in its opening and closing movements. The pressure medium for operating this modified construction of fuel valve is also the fluid which is supplied to the engine for combustion, the pressure fluid for opening the valve being transmitted by pipe 19 to passage 41 leading to an annular chamber 42, such chamber preferably and as shown being formed by reducing the diameter of the valve spindle 43. The pressure of the fluid in this chamber acts on the annulus formed by thus reducing the size of the spindle 43, and raises the conical tip of such spindle from the passage leading into the combustion space. Closure of the valve is effected by pressure fluid from pipe 20 entering chamber 44, where it acts on piston 45. This piston has a close but free sliding fit with the walls of the chamber, and the effective areas in chamber 44 and chamber 42 are shown as sufficient to close the valve quickly without depending on the pressure of spring 46, which may be quite light, and thus avoid the loss of spraying pressure incident to a heavy spring. Connection 47, leading to any desired point, is also provided for carrying off fluid leaking past piston 45.

With a valve constructed according to Fig. 2, it will be seen that the tapered or conical end of spindle 43 entirely fills the valve seat when the valve is closed. There will thus be practically no oil left between the valve and seat when the valve is closed, as in closing any oil adhering to the seat will be forced by the valve into the passage leading to the combustion space and not be drawn back into chamber 42, as would be the case with a valve closing against the flow of fuel and moving away from the cylinder in its closing movement. The quick closing of the valve, also, acts to prevent any dripping of oil into the cylinder after the valve closes, thus aiding in securing the feed of fuel in accurately measured fuel charges.

It will be understood that the invention is not limited to the construction and arrangement of parts shown, but that various changes may be made therein while still retaining the invention defined by the claims.

What is claimed is:

1. The combination with an internal combustion engine, of means for supplying fuel thereto under pressure, a fuel valve, means for opening said valve, a connection to the

- fuel valve arranged to apply seating pressure on said valve by the fuel, and a member arranged to be actuated at the end of the injection period for admitting fuel under pressure to said connection. 5. The combination with an internal combustion engine, of means for supplying fuel thereto under pressure, means for opening said valve by the pressure of said fuel, a connection to the fuel valve arranged to apply seating pressure on said valve by the fuel, and a member arranged to be actuated at the end of the injection period for admitting fuel under pressure to said connection. 2. The combination with an internal combustion engine, of means for supplying fuel thereto under pressure, means for opening said valve by the pressure of said fuel, a 10 connection to the fuel valve arranged to apply seating pressure on said valve by the fuel, and a member arranged to be actuated at the end of the injection period for admitting fuel under pressure to said connection. 15. 3. The combination with an internal combustion engine, of means for supplying fuel thereto under pressure, a fuel valve, means for opening said valve in timed relation to the piston stroke by the pressure 20 of the pumped fuel, a connection to the fuel valve arranged to apply seating pressure on said valve by the fuel, and a member arranged to be actuated at the end of the injection period for admitting fuel under pressure to said connection. 25. 4. The combination with an internal combustion engine, of means for supplying fuel thereto under pressure, a fuel valve, means for opening said valve, a connection to the fuel valve arranged to apply seating pressure on said valve by the fuel, a by-pass valve associated with the fuel supplying means and controlling said connection, and a member co-operating with the fuel supplying means and said by-pass valve and arranged to open the latter at the end of the injection period. 30. 5. The combination with an internal combustion engine, of means for supplying fuel thereto under pressure, a fuel valve, means for opening said valve in timed relation to the piston stroke by the pressure of said fuel, and means for exerting seating pressure on said valve by said fuel at variable 35 times. 40. 6. The combination with an internal combustion engine, of means for supplying fuel thereto in excess of the maximum fuel requirements of the engine, a fuel valve, means for opening said valve in timed relation to the piston stroke by the pressure of said fuel, and means for exerting seating pressure on said valve by said surplus pumped fuel at variable times. 45. 7. The combination with an internal combustion engine, of a pump arranged to supply fuel thereto in excess of the maximum fuel requirements of the engine, a fuel valve, means associated with said pump and fuel valve for opening the latter in timed relation to the piston stroke by the pressure of the pumped fuel, a connection from the pump to the fuel valve arranged to apply; seating pressure on said valve by said surplus fluid, and a valve actuated at the end of the injection period for opening said connection. 55. 8. The combination with an internal combustion engine, of a fuel pump arranged to supply fuel thereto in excess of the maximum fuel requirements of the engine, a fluid pressure actuated fuel valve, means for opening said valve in timed relation to the piston stroke by the pressure of said fuel, a by-pass valve associated with said pump and fuel valve, and means including governor mechanism for opening said by-pass valve to apply seating pressure of the surplus pumped fuel to said fuel valve at variable times. 60. 9. The combination with an internal combustion engine, of a fuel pump arranged to supply fuel thereto in excess of the maximum fuel requirements of the engine, a fluid actuated fuel valve, a valve casing therefor, a connection from said pump for supplying fuel under pressure to open said fuel valve, a connection from said pump to said valve casing for admitting fuel under pressure thereto to close said fuel valve, a by-pass valve associated with said pump and controlling said latter connection, and governor mechanism for opening said by-pass valve at variable times in accordance with the engine load. 65. 10. The combination with an internal combustion engine, of a fuel pump arranged to supply fuel thereto in excess of the maximum fuel requirements of the engine, a fuel valve and casing therefor having a chamber therein to receive fuel under pressure for exerting seating pressure on said fuel valve, a piston in said chamber on which such pressure acts, a connection from said pump to said fuel valve for opening the same by the pressure of the pumped fuel, a connection from said pump to said chamber for admitting fuel under pressure thereto, and a governor controlled valve on said latter connection. 70. 11. The combination with an internal combustion engine, of a fuel supply pump delivering charges of fuel in excess of the maximum fuel requirements of the engine, a fuel valve, means for opening said valve, a connection from the pump for exerting seating pressure on said fuel valve by the surplus fuel delivered by the pump, a connection for returning excess fuel to the fuel supply, and a valve on said last mentioned connection opened by the fuel pressure after the fuel valve is closed. 75. 80. 85. 90. 95. 100. 105. 110. 115. 120. In testimony whereof, I have hereunto set my hand.

OLAV ESKIL JORGENSEN.
